CLAIM

The ornamental design for a heater for dispensing air treatment chemicals, as shown and described.

DESCRIPTION

In a preferred embodiment the nature of this product is as a heater that accepts a wicked reservoir bottle and dispenses an insecticide or fragrance from the wick of the bottle to the surrounding environment.

FIG. 1 is a left, top, frontal perspective view of a first embodiment of a heater for dispensing air treatment chemicals of our new design;

FIG. 2 is a front elevational view thereof;

FIG. 3 is a left side elevational view thereof, the right side elevational view thereof being a mirror image thereof;

FIG. 4 is a top plan view thereof;

FIG. 5 is a bottom plan view thereof;

FIG. 6 is a rear elevational view thereof;

FIG. 7 is a left side elevational view of a second embodiment thereof which is identical to the first embodiment, but for the depiction of an environment of a switch on one side that controls the heater;

FIG. 8 is a view similar to FIG. 7 of a third embodiment which is identical to the FIG. 7 embodiment, except that the switch is now part of the environment, and a power cord environment is depicted for use therewith, and some of the bottom view features are altered as depicted in FIG. 9; and,

FIG. 9 is a bottom plan view of the third embodiment.

The broken line representations of a switch in FIGS. 7 and 8, a power cord in FIG. 8, and bottom structures in FIGS. 5 and 9, are for purposes of illustration only and do not represent part of the claimed structure.
